(57) **CLAIM**

The ornamental design for a general merchandise vending machine, as shown and described.

DESCRIPTION

FIG. 1 is an isometric view of a general merchandise vending machine;

FIG. 2 is a front view thereof;

FIG. 3 is a rear view thereof;

FIG. 4 is a left-hand side view thereof;

FIG. 5 is a right-hand side view thereof;

FIG. 6 is a top view thereof; and,

FIG. 7 is a bottom view thereof.

In the drawings, the broken lines illustrate environment and form no part of the claimed design.
